CHARLES W. VAN DE MARK AND CALVIN MOORE, OF CLYDE, KANSAS.

TONGUE-SUPPORT.

SPECIFICATION forming part of Letters Patent No. 357,428, dated February 8, 1887.

Application filed November 12, 1886. Serial No. 218,705. (No model.)

To all whom it may concern:

Be it known that we, CHARLES W. VAN DE MARK and CALVIN MOORE, of Clyde, in the county of Cloud and State of Kansas, 5 have invented a new and useful Improvement in Tongue-Supports, of which the following is a specification.

This invention is an improved tongue-support; and it consists in certain features of construction and novel combinations of parts, as will be described.

In the drawings, Figure 1 is a perspective view of the improvement. Fig. 2 is a vertical longitudinal section thereof, and Fig. 3 is 15 a perspective detail view of the spring.

The hounds A A and tongue B may be of the ordinary construction, connected by the common cross-shaft C, as shown. The spring D is formed of the cross-bar E, of spring 20 metal or material, and the arms F F, which latter are also of spring material, are secured at one end to the bar E and extend forward therefrom. At its ends the bar E is secured to the hounds or other support. This is 25 preferably accomplished in the manner shown by fitting staples G over the ends of said cross-bar and securing such staples to the hounds, the ends of the cross-bar E being bent, forming projections e, which prevent the 30 bar from becoming detached from the staples. This form of connection with the hounds permits the necessary movements of bar E for such bar to act as a spring.

By threading the arms of the staples G and 35 providing nuts g on the arms below the hounds the cross-bar may be held close to the hounds, or permitted to have more or less play, according to the angle at which it is desired to support the tongue.

The arms F F extend, in use, over the shaft 40 C, and then below and bear under the tongue at H. At their forward ends, where they bear under the tongue, the arms are rounded at f f, in order that they may move easily 45 against the tongue and not to any great extent wear the same.

Instead of resting the arms F directly on the shaft, it is preferred to provide an intermediate connection between such parts. This 50 connection in the construction shown is a bolt, I, having a threaded shank, i, secured to the

arm, and a forked head, J, fitted over the shaft. We employ one of these connections for each arm, and by preference they are secured adjustably to said arm. This is effected 55 by threading the shanks i and turning nuts K thereon above and below the arm. By properly turning these nuts the arm may be secured at any suitable distance above the hounds, as may be desired, in order to vary 60 the height at which the tongue will be supported.

The operation will be readily understood from the drawings and foregoing description.

It will be seen that the tongue may be so 65 supported as to relieve the team of its weight, and that the devices for so supporting the tongue are simple, inexpensive, and not likely to get out of order. Now, the construction and arrangement of the hounds, tongue, and 70 shaft C, as shown, are common, and while our invention gives good results with such arrangement, it will be understood that it might be employed in connection with other forms and arrangement of hounds, tongue, and shaft 75 C, and with a different form of connection between the tongue and vehicle.

The hounds form the support for the spring, and the shaft C a fulcrum therefor, as will be 80 understood from the foregoing description.

Having thus described our invention, what we claim as new is—

1. In a tongue-support, and as a new article of manufacture, a spring, D, consisting of a cross-bar, E, and spring-arms F, secured at 85 one end to such bar, substantially as set forth.

2. The combination, in a tongue-support, of the tongue, a spring-support, a fulcrum, and a spring having a cross-bar secured to the spring-support, and spring-arms secured to 90 such cross-bar extended forward over the fulcrum, and having their forward ends bearing under the tongue, substantially as set forth.

3. The herein-described spring for tongue-supports, consisting of the cross-bar E, having 95 projections e at its ends, and the arms F, secured at one end to cross-bar E, and having their opposite or forward ends rounded, substantially as and for the purposes specified.

4. The combination, with the tongue, the 100 shaft, and a spring-support, of the spring secured on the spring-support, and having an

arm or arms extended forward over the shaft, and thence under the tongue, and a connection, I, having a forked head, J, fitting over the shaft O, a threaded shank, *i*, extended 5 through the arm, and nuts K, all arranged and operating substantially as and for the purposes specified.

5. The combination of the hounds A, the tongue B, the shaft C, the cross-bar E, having 10 projections *e* at its ends, the staples G, fitting

over said bar and securing it to the hounds, the arms F, having their forward ends rounded at *f* and bearing under the tongue, and the connections I between arms F and shaft C, all substantially as set forth.

CHARLES W. VAN DE MARK.
CALVIN MOORE.
